Attorney

UNITED STATES PATENT OFFICE.

LEO LEON WILLIAMS, OF PORTLAND, OREGON.

DISPLAY STAND.

Application filed November 24, 1925. Serial No. 71,126.

This invention relates to improvements in store furniture, and is more particularly adapted to a display stand for displaying merchandise put up in package form.

One of the important objects of the present invention is to provide a display stand which includes a base, and an upwardly extending rod associated therewith, the upper end of the rod being pointed to facilitate the placing of the packages of merchandise to be displayed on the rod, it being understood of course that the packages are provided with suitable eyelets to permit the same to be placed on the rod and arranged a number of packages in superposed relation.

A further object is to provide a display stand of the above mentioned character which is particularly adapted to be used in supporting and displaying packages which are made of waxed or glazed paper to contain merchandise which is oiled or buttered or prepared in oil or butter, such as potato chips, salted peanuts, etc., which packages by reason of the slickness of the paper will not readily lend themselves to stacking or piling, and also to be used in supporting and displaying packages which by reason of their irregular shape do not lend themselves readily to piling or stacking, such packages being sealed and provided with suitable eyelets in the sealed portions thereof whereby the packages are placed on the upstanding rod of the stand as well as being easily removed therefrom.

A further object is to provide a display stand of the above mentioned character which is particularly adapted to be used in supporting and displaying packages which are formed of transparent material to enable the contents thereof to be readily visible, the packages being sealed and provided with suitable eyelets in the sealed portions thereof whereby the packages may be easily placed on the upstanding rod of the stand, as well as being easily removed therefrom.

A still further object is to provide a display stand of the above mentioned character which is simple in construction, inexpensive, strong, and durable and further well adapted to the purpose for which it is designed.

Other objects and advantages of the invention will become apparent during the course of the following description taken in connection with the accompanying drawing.

In the accompanying drawing forming a part of this application and in which like numerals designate like parts throughout the same:

Figure 1 is a perspective view of the display stand embodying my invention.

Figure 2 is a top plan view, and

Figure 3 is a side elevation of one of the packages which is adapted to be supported and displayed on the stand.

In the drawing wherein for the purpose of illustration is shown the preferred embodiment of my invention, the numeral 1 designates the circular base of the display stand, the same being formed of a single strand of wire bent into ring formation and having the ends of the wire soldered or otherwise secured together in any well known manner. A brace wire 2 extends diametrically across the circular base 1, and has its ends secured to the ring forming the base at diametrically opposite points in the manner as clearly illustrated in the drawing. An elongated rod or spindle 3 extends upwardly from the central portion of the circular base and has its lower end brazed or soldered to the intermediate portion of the brace rod 2. This spindle is of a suitable length, and if desired, the upper end thereof may be pointed. The purpose of the aforementioned spindle will be hereinafter more fully described.

For the purpose of bracing and further supporting the spindle in a rigid vertical position, there is provided the additional brace rods 4, 5, and 6 respectively. Each of the additional brace rods is of a length greater than the first mentioned brace rod 2, and as is more clearly illustrated in Figure 1, each of these rods is bent at its intermediate portions so that the ends thereof are arranged in divergent relation, and the free ends of each of these last mentioned bracing rods are secured at diametrically opposite points to the ring or circular base 1 by soldering or brazing the same thereto. The additional brace rods are preferably arranged at points equidistant from each other as is more clearly illustrated in Figure 2 and preferably the additional brace rods are placed sixty degrees apart on the circular base.

The bent portions of the several brace rods 4, 5, and 6 are soldered or brazed at their point of intersection to the spindle 3 at a point adjacent the lower end thereof as in-

dicated at 7, and in this manner, the spindle will be sufficiently braced so as to render the same rigid and capable of receiving a number of packages of merchandise which 5 are to be displayed and supported on the stand.

A stand of the above mentioned character is particularly adapted for use in grocery stores for displaying merchandise put up 10 in transparent packages such as potato chips, cakes, candy, and the like. The open end of the package is sealed in the usual manner, and a suitable outlet such as is shown at 8 extends through the sealed portion 9 of the 15 package 10 in the manner clearly shown in Figure 3. The provision of the eyelet enables each package to be easily placed on the spindle 3, and a number of packages can be accommodated, and when the same are 20 placed on the spindle of the band, the packages will be disposed in superposed relation, and if desired, the same are preferably arranged in criss cross formation so as to more easily display the merchandise. 25 This is shown more clearly in the dotted lines in Figure 1 of the drawing.

A display stand of the above mentioned character will not occupy a considerable amount of space, and may be easily placed 30 upon a counter or table, and the packages may be readily and easily removed there-

from without any difficulty. The simplicity in which my improved display stand is constructed, renders the same inexpensive, yet strong and durable.

While I have shown the preferred embodiment of my invention, it is to be understood that minor changes in the size, shape, and arrangement of parts may be resorted to without departing from the spirit or scope 40 of the invention.

Having thus described the invention, what I claim as new is:—

A display stand comprising a ring-like base, a brace rod extending diametrically 45 across the ring-like base, an article receiving spindle having its lower end secured to the intermediate portion of the brace rod and extending upwardly therefrom, and a series of additional brace rods extending diametri- 50 cally across the ring-like base, the free ends of the additional brace rods being secured to the ring-like base at diametrically opposite points, the intermediate portions of the additional brace rods being bent and intersecting one another, the intersecting portions of the additional brace rods being secured to the spindle at a point above the lower end thereof.

In testimony whereof I affix my signature.

LEO LEON WILLIAMS.
